UNITED STATES PATENT OFFICE.

GEORGE M. WILLIAMS, OF ELIZABETH, NEW JERSEY, ASSIGNOR TO P. LORILLARD COMPANY, OF NEW YORK, N. Y., A CORPORATION OF NEW JERSEY.

ART OF APPLYING TISSUE WRAPPERS TO CIGARS, &c.

1,271,251.

Specification of Letters Patent.

Patented July 2, 1918.

Application filed April 4, 1917. Serial No. 159,665.

To all whom it may concern:

Be it known that I, GEORGE M. WILLIAMS, a citizen of the United States, residing at Elizabeth, in the county of Union and State 5 of New Jersey, have invented certain new and useful Improvements in the Art of Applying Tissue Wrappers to Cigars, &c., (Case B,) of which the following is a specification.

10 This invention relates to improvements in the art of applying inclosing wrappers to articles, and more particularly to mechanisms for producing end twists to the wrapper after the inclosure has been wrapped about 15 the article.

While the present invention is adapted to supply wrappers to various objects, as for instance, stick candy, it is more particularly designed to meet the conditions presented in 20 applying inclosing wrappers to cigars, che-roots, etc.

As pointed out in a companion application (Ser. No. 159,664) filed concurrently herewith, cigars, etc., which are completed 25 by a leaf tobacco wrapper, the integrity of which must be maintained to permit salability, have certain inherent characteristics which tend to form weaknesses when attempts are made to apply an inclosing 30 wrapper to the completed cigar. The application of excessive pressure, or movements which may tend to loosen the spiral windings of the leaf wrapper, all tend to damage the cigar and affect its salability.

35 These conditions are met in part by employing an inclosing wrapper of thin flexible tissue paper which will conform more or less to the shape of the cigar, increasing the ability to retain the initial aroma, etc., and 40 which may be applied without producing material strains on the cigar wrapper. This, however, adds to the problem of applying the wrapper mechanically due to the frailty of the paper wrapper. Hence, both the cigar 45 and its inclosing wrapper present inherent difficulties which do not become material under manipulation by hand, but which become important when mechanical manipulating means is employed.

50 Obviously, the cost of applying the wrapper is an element of importance commercially, and this cost is materially affected

by the length of time required to apply the wrapper and the desirability of uniformity in product. Hand manipulation, owing to 55 the care required, tends to low capacity and higher cost, requiring more or less expert operatives. Increasing capacity by mechanical manipulation involves meeting the inherent difficulties. 60

In the companion application referred to these problems are met by applying the inclosing wrapper to the cigar by hand and then employing mechanism for producing the end twists, the latter operation being had 65 without affecting the integrity of the cigar or the inclosing wrapper. Twisting of the ends is had by the use of rotatable twisting mechanism, the body of the wrapper and the cigar being held stationary by a hand 70 of the operator, the twisters turning the ends of the wrapper to develop the twists. This practically assures uniformity in the twist development and of product, permits the twisting to be had at high speed as compared with hand manipulation, and at the same time leaves one hand of the operator 75 free to prepare for applying a wrapper to the succeeding cigar, it being understood that the attention of the operator need not be concentrated on the mechanism after the twisting operation begins.

In such embodiment the leaf wrapper of the cigar is not subjected to material pressure or strains tending to loosen the wrapper, the cigar being held stationary by being grasped by the operator's fingers and therefore under control as to pressure application. 85

The present invention is designed to meet 90 the same problems, but in the present embodiment the twist development is had by rotating the cigar and the body of the inclosing wrapper, the wrapper ends being held stationary.

Obviously, this reversal in the manner of producing the twist involves additional difficulties where mechanical rotating mechanisms are employed. For instance, in the 10 companion embodiment, the effect on the leaf wrapper is more or less indirect—provided by the twist development alone; in employing the reverse arrangement, this indirect effect is present, but, in addition, a

direct effect is produced by the necessity of mechanically gripping the cigar without liability of damaging it by pressure application, and then rotating the gripped cigar 5 against the resistance of the twist development without damaging the cigar by pressure or developing movements tending to loosen the leaf wrapper.

The present embodiment contemplates a 10 structure capable of meeting these conditions; it also contemplates a structure by means of which both hands of the operator remain free during the twisting operation to permit preliminary manipulation of the 15 cigar and inclosing wrapper and increase capacity, thus tending to decrease the productive cost.

To these and other ends, the nature of which will be readily understood as the invention is hereinafter disclosed, said invention consists in the improved construction and combination of parts hereinafter fully described, illustrated in the accompanying drawings, and more particularly pointed 25 out in the appended claims.

In the drawings, in which similar reference characters indicate similar parts in each of the views—

Figure 1 is a front elevational view showing one way in which the general principles of my invention may be carried out.

Fig. 2 is a top plan view of the same.

Figs. 3 and 4 are sectional views taken on lines 3—3 and 4—4 respectively of Fig. 1.

Fig. 5 is a detail sectional view taken on line 5—5 of Fig. 4.

Fig. 6 is a sectional view taken on line 6—6 of Fig. 1.

Fig. 7 is a sectional view taken on line 40 7—7 of Fig. 2.

Fig. 8 is a sectional view taken longitudinally of a gripping unit.

20 designates a table on which is mounted a support for the wrapped cigar during the end-twisting operation. This support may be and preferably is located in rear of a surface on which the inclosing wrapper may be placed around the article—for example, a cigar—with the ends free and un-twisted, being tube-like in form. It will be obvious, however, that the wrapping operation may take place at a different point, the present disclosure being intended to operate upon a cigar inclosed in this manner.

55 In the companion application referred to the relative location of the support and wrapping surface is indicated and claimed, as is the use of a pasting mechanism for "tacking" the inclosing wrapper in position, the support in that embodiment being in the form of two members spaced-apart and maintained stationary during the twisting operation.

In the present embodiment, this support, 65 also in the form of two spaced-apart mem-

bers axially-aligned and having a fixed location on the table, is adapted to grip and rotate the wrapped cigar. By gripping the free ends of the wrapper in suitable fingers held stationary during the support rotation, 70 twist development is had at the ends of the article.

Each member of the support is in the form of an element formed in two segments or sections 21 and 22, these segments, when 75 in proper relation forming a cylindrical structure through which the wrapped cigar extends, the two cylindrical structures of the two members of the support, being axially aligned. Each segment is provided with a 80 yieldable face adapted to frictionally grip the wrapped article when positioned, a simple form of such face being a resilient leaf spring segment 23 (Fig. 4) secured at one end to the segment, the other end being 85 free. This permits a yielding pressure to be placed on the wrapped article sufficient to rotate it but insufficient to damage the cigar or its inclosing wrapper during the end-twisting operation. Obviously, other means 90 for accomplishing these ends may be employed.

Segment 21 is carried by a suitable member 24, carried by the table and having a configuration to receive the segment, while 95 segment 22 is carried by a member 25 pivotally connected to member 24, as at 26, member 25 also having a configuration to receive segment 22. Members 24 and 25 may be considered as a pair of jaws relatively 100 movable on pivot point 26 to complete the ring-shaped opening for the wrapped article, or to open said opening for the reception or removal of the wrapped article. These members may have a mating relation 105 at their opposing faces, and may have means for preventing relative axial movement, if desired. A means for this purpose is indicated in Fig. 1 as a projection 27 on one member adapted to enter a complementary recess 28 formed in the other member.

As shown more particularly in Fig. 5 segments 21 and 22 are each provided with a slot 29 these slots being located on a side face of and extending from end to end of 110 the respective segments, being concentric with the outer peripheral face of the segments. Each jaw member carries one or more pins or screws 30 extending into slots 29, the pin and slot configuration forming 115 guiding and retaining means for the segments during rotation, it being understood that when the jaws are in closed position, slots 29 will produce a complete annular slot, thus enabling the segments to freely 120 travel from one jaw member to the other.

Each segment also has its periphery formed with a toothed face 31, these faces, when the jaws are closed, forming a complete gear face, the segments in this posi- 130

tion forming an annular gear meshing with a gear 32 mounted on shaft 33 extending through jaw members 24 of each of the support members.

5 Shaft 33 also carries a pinion 34 adapted to coöperate with a mutilated gear 35 mounted on a shaft 36 located below the table, said shaft 36 being driven in any suitable manner, a worm and gear structure 37 being shown as an example, it being understood that any well known drive mechanism may be employed and that any desired control mechanism may be used to control the operations of the mechanisms described herein, either for continuous or for intermittent operation.

Shaft 33 and gear 35 preferably carry complementary structures adapted to retain shaft 33 from rotation when pinion 34 is disengaged from the teeth of gear 35, the structures being shown as a member 38 carried by gear 35 and having a curved face 38^a, and a member 39 having a depression 39^a complementary to such face, this being 25 one form of a well-known mechanism adapted for the purpose, it being obvious that various other structures may be employed.

As will be understood, engagement of pinion 34 and the toothed face of gear 35 30 will cause rotation of the ring-shaped gears when shaft 36 is rotated; when the engagement of pinion and gear is broken, members 38 and 39 are brought into coöoperative relation, holding shaft 33 against rotation during rotation of shaft 36 an angular distance equal to the length of face 38^a which substantially corresponds to the length of the arc in which the teeth of gear 35 are omitted.

40 The parts are so arranged that the jaws are in closed position when pinion 34 and gear 35 engage and remain closed throughout the period of such engagement, thereby presenting segments 21 and 22 in complete ring formation during this period. Furthermore, the rotating mechanisms of the segments of the two members of the support are so formed and connected as to move in unison, thus preventing any relative movement between the ring-shaped members of the two members of the support. Consequently, the fact that the contact of spring segments 23 with the wrapped cigar is had at spaced-apart points in the length of the 55 cigar is immaterial, no relative movement tending to produce a twisting or wrapper-unwinding action on the cigar being had.

Opening and closing of the jaws is had while members 38 and 39 are active and 60 while shaft 33 is held from rotation. This action is provided by moving member 25 on its pivot, said member having an arm 25^a connected to a pivoted lever 40 by an adjustable connection 41, said lever carrying a 65 roller 42 adapted to coöperate with a cam

43—in this instance shown as a face cam—roller 42 being held in contact with the cam by the action of a spring 44. Cam 43 is mounted on shaft 36 and operates to move member 24 to closed position, spring 44 moving member 25 to its open position when the lead of the cam permits. Obviously, this particular structure for moving member 24 is but one of a number of operating mechanisms adapted for the purpose.

70 Each member of the support preferably has its individual member-moving mechanism, and these mechanisms preferably operate in unison in order that members 25 may move to open and closed positions 75 currently.

As one of the segments 21, 22 is carried by each of members 24 and 25, the proportions and timing of the connections,—gears, etc.—are such that at the completion of rotational 80 movements of the ring formation, the segments come to rest with the end faces substantially aligned with the meeting line of the opposing faces of the jaws; thus retaining the segments out of the cigar-entering 85 passage formed between the jaws in open position. Obviously, there is no requirement that the same segment be positioned in the same member at the beginning and close of the rotational movements.

90 By proper proportioning of parts this result can be obtained with respect to the segment in member 24, this segment being maintained in this position through its engagement with gear 32, locked against movement 95 at this time. Obviously, the segment in member 25 will also be properly positioned in that member prior to movement of member 25 to open position. To prevent material movement of the segment in member 25 when the latter is moved from its closed position I employ a suitable latch device which engages a segment to prevent its shifting during this period. A simple structure for this purpose is shown as a pivoted member 100 45 having an offset 45^a movable in a slot 25^b of member 25 to and from a position between two teeth of the segment. Member 45 is under tension of a spring 46 tending to move the member to its operative tooth-engaging 105 position. This engagement is had when member 25 is opened and is broken as the member 25 approaches its closed position, latch member 45 contacting with a stop pin 47 carried by member 24 which pin limits the travel of member 45 to its latching position in member 25, so that as member 25 110 continues its movement to closed position relative movement between member 25 and finger 45^a will be had, releasing the segment 115 from latch activity. When member 25 opens, reverse relative movement is had and latch activity occurs.

120 As will be understood, the jaw 25 is moved from closed to open position and return 125

while members 38 and 39 are active, remaining in open position a length of time sufficient to permit removal of the completely-wrapped cigar and the insertion of the cigar 5 to be completed. The length of time may be controlled in any of a number of obvious ways, as by the configuration of cams 43, shaft 36 then having a substantially continuous operation which may be under the control of the operator, or suitable clutch mechanism may connect shaft 36 with a power device in such manner that the clutch engagement is had at will and the engagement broken when jaw 25 reaches its open position. Both types of control are well-known 10 in general mechanism operations.

With the parts in the position shown in full lines in Fig. 3 and the wrapped article inserted, rotation of shaft 36 causes cams 43 20 to close jaws 25, releasing the gear segments carried thereby during the closing movement, thus gripping the cigar between spring segments 23 with a pressure sufficient to cause the cigar to travel with the ring 25 gears during their rotation, but insufficient to damage the cigar. Pinion 34 is then rendered active by the toothed face of gear 35, positively rotating the ring gears in unison and giving the wrapped cigar the desired 30 rotating movement, the cigar axis being substantially coincident with the aligned axis of the ring gears, a position maintained throughout rotation. During this time the ends are twisted by holding the free ends 35 of the wrapper against rotation, thus producing a twist development at such ends. As pinion 34 leaves its engagement with gear 35, members 38 and 39 become active to hold shaft 33 stationary, and cams 43 then permit springs 44 to move jaws 24 to open position, latch member 45 being made active 40 during such movement.

It will be seen that the facial contact of wrapper and spring segments becomes fixed 45 by the closing of the jaws, this contact remaining constant throughout the rotation, thus eliminating any tendency to affect the condition of the cigar by shifting the point of pressure application.

50 The members of the support are spaced apart a distance less than the length of the cigar thus leaving the ends of the latter, together with the free ends of the wrapper, projecting beyond these members when the 55 cigar is clamped or gripped. Consequently, the wrapper ends may be readily grasped or gripped and held during the rotating movement. And since the yielding action of the spring segments 23 accommodates for 60 variation in thickness of the cigar, accurate positioning of the wrapped cigar is not absolutely essential, the forced movement of the ring gears in unison assuring proper action without damage to the cigar wrapper.

65 In addition, the use of the spaced sup-

ports for the article is of positive advantage. For instance, the length of the article is such that the support must be effective at considerable distance from the center, since the twisting action takes place at the ends and there is no rigid connection between the end supports—the grippers—and the article support, and it is desirable to prevent any liability of a wobbling action of the article during the twist-development rotation; a single wide support would be less effective owing to the difficulty of providing yieldable elements properly positioned to take care of the somewhat irregular contour of the cigar or other article. By the use of the spaced supports, each carrying its individual clamping elements, these difficulties are overcome.

With the wrapped cigar positioned, gripped and rotated in this manner, the wrapper ends may be held in any suitable manner, as by being grasped or gripped between fingers of the operator's hands. However, I prefer to provide mechanical gripping mechanisms movable into and out of gripping positions, thereby leaving the hands of the operator free to prepare the succeeding cigar for the end twisting operation, as well as reducing the necessity for concentrating the attention of the operator on the twisting operation.

As more fully pointed out in the companion application, certain difficulties are presented in providing mechanical end-twisting where the article is formed with a 100 wrapper or other suitable surface easily damaged and where it is absolutely essential that no material damage occurs. And in the present embodiment of the invention I prefer to meet these difficulties in a somewhat similar manner, by providing opposing gripping fingers which afford sufficient resistance to insure twist development, but in which this resistance is insufficient to prevent shifting of the ends in directions to withdraw them by the twist development action. I also prefer to compensate for the changes in end configuration produced by the twist development, thus permitting the twisting action to have its natural effect on 115 the wrapper portions affected by the twist development.

As the gripping mechanisms are substantial duplicates excepting as to "right" and "left" operation, a description of one will 120 suffice.

48 indicates a plate mounted on table 20 between guides 49 to permit endwise adjustment, said plate carrying a pedestal 50 in which is mounted a rod or support 51 125 adjustable endwise in such pedestal. Said rod has its inner end formed with a head 51^a.

Mounted on rod 51 is a sleeve 52 longitudinally shiftable on said rod toward and from head 51^a, said head limiting the ad- 130

vance movement of the sleeve. Said sleeve has fixedly secured thereto a member 53 carrying pivoted elements 54 in which are adjustably and removably mounted fingers 55, the latter being located on diametrically opposite sides of the rod axis. As shown in Fig. 8, fingers 55 are firmly held in position by adjusting screws 55^a, adjustment of the latter controlling the positions of the gripping faces in closed position and hence the gripping pressure. As shown, the fingers preferably have substantially flat opposing faces, these faces preferably decreasing in width toward the advance end. Member 53 may be adjustable endwise, if desired.

Sleeve 52 also carries a cam structure 56 slideable on the sleeve, the sleeve having a head 52^a with which the cam structure co-operates intermittently.

57 indicates a lever pivoted, as at 57^a, to a support 58 preferably connected to plate 48, said lever having its lower end co-operating with a cam 59 mounted on and rotatable with shaft 36 but preferably slideable thereon, the lever carrying a pin or roller 57^b entering a cam groove 59^a, said groove controlling the shifting movements of the lever. The upper end of lever 57 co-operates with cam structure 56 to move the latter axially, suitable connections being provided, as, for instance, pins 57^c entering into a circumferential groove 56^a of the cam structure.

With jaw 25 in open position, as in Figs. 1 and 2, the gripping mechanisms are positioned with fingers 55 in their outer or open positions and withdrawn from their advance or operative positions. The cycle of operation of each mechanism is substantially as follows:

As shaft 36 rotates cam 59 causes movement of lever 57 to advance cam structure 56. Since the completion of the previous cycle has left rollers 54^a carried by elements 54 in position at the inner end of the inclined face of the cam structure, and no material resistance against advance movement of sleeve 52 is present at this time, while elements 54 are under the tension of springs 54^b tending to maintain the rollers in such inner positions, advance movement of cam structure 56 will cause similar movement of sleeve 52 and parts carried thereby on rod or support 52, all parts traveling in unison.

55 This movement continues until sleeve 52 contacts with head 51^a, preventing further sleeve movement in this direction. Cam 59 however is still active to move lever 57 to advance cam structure 56, thus resulting in 60 rendering the cam structure active to close the fingers, rollers 54^a being spread apart by the advance of the cam structure. The lead of cam 59 is arranged to maintain the fingers in closed position for a predetermined time preferably covering the period

during which the ring gears of the cigar support are rotating. During this period the fingers are held from rotation by the pin and slot connection between rod 51 and sleeve 52 (Fig. 7).

At the conclusion of the twisting operation, cam 59 causes lever 57 to reverse its movement. This causes cam structure 56 to move outward, permitting rollers 54^a to travel over the inclined face to their inner positions under the action of springs 54^b. Since cam structure 56 is free to move on sleeve 52, this action of the rollers tends to retain sleeve 52 in its advance position allowing the fingers to open before leaving such position. The continued travel of the cam structure 56 brings it into contact with head 52^a whereupon the sleeve and cam structure travel together to the outer positions, completing the cycle.

The combined action of the cigar rotating support and the stationary gripping fingers, results in developing a twist-formation in advance of the fingers, the untwisted portion of the ends withdrawing in the direction of and due to the twist development, the fingers being held from endwise movement during such development. The preferred shape of the fingers permits the natural effect of the twisting action to take place on such ends thus placing no material strains on the wrapper. Absence of such strains permits the use of thin tissue paper to form the inclosing wrapper.

It will be readily understood that after the wrapped cigar has been positioned the apparatus completes the operation without further attention, leaving the operator free to prepare the succeeding cigar to replace the one so completed.

Adjustment is provided to accommodate for the wrapping of cigars differing in length. This is had through adjustment of plates 48 in guides 49, this plate controlling the positions of the several parts, cam 59 having a slideable connection with shaft 36, and support 58 being formed with arms 58^a on opposite sides of cam 59 and thus fixing the position of cam 59 on the shaft. Hence, each gripping mechanism is in the form of a unit adjustable bodily in directions to increase or decrease the distance between the opposing mechanisms and without disturbing the operating connections.

The specific form of the gripping fingers 55 is not claimed herein, claims therefor being presented in the companion application.

While I have herein shown what may be considered a preferred embodiment of the present invention, changes and modifications therein may be required or desired to meet various exigencies of use, and I desire to be understood as reserving the right to make any and all such changes or modifications as may be found necessary or desirable in so far

as the same fall within the spirit and scope of the invention as contemplated by the accompanying claims.

What I claim is:

5. 1. In mechanisms for inclosing articles in wrappers with twisted ends and operative with tissue wrapper inclosures for cigars, etc., means for supporting and encircling the wrapped article during end-twisting operations, said means including gripping mechanism adapted to receive and grip the wrapped article, and means for moving the wrapped article rotatively when gripped, the gripping contact with the wrapped article remaining constant during article rotation, said gripping mechanism being operative to permit introduction of the wrapped article in directions transverse to the direction of length of the axis of rotation.
10. 2. In mechanisms for inclosing articles in wrappers with twisted ends and operative with tissue wrapper inclosures for cigars, etc., means for supporting the wrapped article during end-twisting operations, said means including gripping mechanism adapted to receive and grip the wrapped article, and means for moving the wrapped article rotatively when gripped, said mechanism and the wrapped article being free from relative movement during article rotation, said gripping mechanism being operative to permit introduction of the wrapped article in directions transverse to the direction of length of the axis of rotation.
15. 3. In mechanisms for inclosing articles in wrappers with twisted ends and operative with tissue wrapper inclosures for cigars, etc., means for supporting and encircling the wrapped article during end-twisting operations, said means including rotatable gripping mechanism for the wrapped article and adapted to maintain a substantially fixed relation to the article during article rotation, said gripping mechanism being operative to permit introduction of the wrapped article in directions transverse to the direction of length of the axis of rotation.
20. 4. In mechanisms for inclosing articles in wrappers with twisted ends and operative with tissue wrapper inclosures for cigars, etc., means for supporting and encircling the wrapped article during end-twisting operations, said means including rotatable gripping mechanism for receiving and embracing the wrapped article to provide a gripping relation therewith, the initial gripping relation remaining constant during article rotation, said gripping mechanism being operative to permit introduction of the wrapped article in directions transverse to the direction of length of the axis of rotation.
25. 5. In mechanism for inclosing articles in wrappers with twisted ends and operative with tissue wrapper inclosures for cigars,
- etc., means for supporting the wrapped article during end-twisting operations, said means including a tubular rotatable gripping element adapted to receive and grip the wrapped article, and means for supporting said element and controlling its path of movement, said means including a tubular rotatable gripping element adapted to receive and grip the wrapped article, said element being operative to permit introduction of the wrapped article in directions transverse to the direction of length of the element axis.
30. 6. In mechanisms for inclosing articles in wrappers with twisted ends and operative with tissue wrapper inclosures for cigars, etc., means for supporting the wrapped article during end-twisting operations, said means including a tubular rotatable gripping element adapted to receive and grip the wrapped article, said element being operative to permit introduction of the wrapped article in directions transverse to the direction of length of the element axis and including a yieldable gripping face, and means for supporting said element and controlling its path of movement.
35. 7. In mechanisms for inclosing articles in wrappers with twisted ends and operative with tissue wrapper inclosures for cigars, etc., means for supporting the wrapped article during end-twisting operations, said means including a pair of spaced-apart axially aligned rotatable tubular gripping elements adapted to receive and grip the wrapped article intermediate its ends, and means for supporting said elements and controlling the paths of movement thereof.
40. 8. In mechanisms for inclosing articles in wrappers with twisted ends and operative with tissue wrapper inclosures for cigars, etc., means for supporting the wrapped article during end-twisting operations, said means including a pair of spaced-apart axially-aligned elements movable in unison and adapted to receive and grip the wrapped article, means for supporting said elements and controlling the paths of element movement, and means for moving the article rotatively while so gripped.
45. 9. In mechanisms for inclosing articles in wrappers with twisted ends and operative with tissue wrapper inclosures for cigars, etc., means for supporting the wrapped article during end-twisting operations, said means including a pair of spaced-apart axially-aligned elements adapted to receive and grip the wrapped article, means for supporting said elements and controlling the paths of element movement, and means for rotating said elements in unison.
50. 10. In mechanisms for inclosing articles in wrappers with twisted ends and operative with tissue wrapper inclosures for cigars, etc., means for supporting the wrapped article during end-twisting operations, said means including a pair of spaced-apart axially-aligned elements adapted to receive and

embrace the wrapped article, means for supporting said elements and controlling the paths of element movement, and means for rotating the elements in unison while in embracing positions.

5 11. In mechanisms for inclosing articles in wrappers with twisted ends and operative with tissue wrapper inclosures for cigars, etc., means for supporting the wrapped article during end-twisting operations, said means including a pair of spaced-apart axially-aligned elements each including members relatively movable to permit positioning of the article and to grip it when positioned, means for supporting said elements and controlling the paths of element movement, and means for moving the article relatively when gripped.

10 12. In mechanisms for inclosing articles in wrappers with twisted ends and operative with tissue wrapper inclosures for cigars, etc., means for supporting the wrapped article during end-twisting operations, said means including a pair of spaced-apart axially-aligned elements each including members relatively movable to permit positioning of the article and to grip it when positioned, means for supporting said elements and controlling the paths of element movement, and means for rotating the elements in unison when said members are in gripping positions.

15 13. In mechanisms for inclosing articles in wrappers with twisted ends and operative with tissue wrapper inclosures for cigars, etc., means for supporting the wrapped article during end-twisting operations, said means including a rotatable gripping element consisting of segmental members combinedly forming a tubular structure into which the wrapped article extends and by which it is gripped, a support for and adapted to carry each member, said supports being relatively movable to open and close the structure, and means for rotating said structure when the supports are in closed position.

20 14. In mechanisms for inclosing articles in wrappers with twisted ends and operative with tissue wrapper inclosures for cigars, etc., means for supporting the wrapped article during end-twisting operations, said means including a gripping structure comprising a pair of segmental members adapted to combinedly receive and grip the wrapped article, a support for each member, said supports being pivotally connected to permit opening and closing of the segments, means for controlling the movements of the supports, and means for rotating the combined segments.

25 15. In mechanisms for inclosing articles in wrappers with twisted ends and operative with tissue wrapper inclosures for cigars, etc., means for supporting the wrapped ar-

ticle during end-twisting operations, said means including a pair of jaw-like members, a sectional gripping structure carried by and adapted to rotate in said members, means for positioning said members and structure in article receiving and gripping positions, and means for rotating said structure when in gripping position.

30 16. In mechanisms for inclosing articles in wrappers with twisted ends and operative with tissue wrapper inclosures for cigars, etc., means for supporting the wrapped article during end-twisting operations, said means including a sectional ring-like gear, a supporting member for each gear section, said members being pivotally connected to permit relative movements toward and from a section-mating position, gear-rotating means, and means for providing member movements, said latter means and the gear-rotating means being relatively timed to prevent concurrent movements.

35 17. In mechanisms for inclosing articles in wrappers with twisted ends and operative with tissue wrapper inclosures for cigars, etc., means for supporting the wrapped article during end-twisting operations, said means including a sectional ring-like gear, a supporting member for each gear section, said members being pivotally connected to permit relative movements toward and from a section-mating position, and means for rotating said gear when the supporting members are in section-mating position.

40 18. In mechanisms for inclosing articles in wrappers with twisted ends and operative with tissue wrapper inclosures for cigars, etc., means for supporting the wrapped article during end-twisting operations, said means including a sectional ring-like gear, a supporting member for each gear section, said members being pivotally connected to permit relative movements toward and from a section-mating position, and gear-rotating means intermittently operative and controlled to locate sections in positions relative to a predetermined mating-like position when said means is rendered inactive.

45 19. In mechanisms for inclosing articles in wrappers with twisted ends and operative with tissue wrapper inclosures for cigars, etc., means for supporting the wrapped article during end-twisting operations, said means including a sectional ring-like gear, a supporting member for each gear section, said members being pivotally connected to permit relative movements toward and from a section-mating position, intermittently-operative gear-rotating means, and mechanism for controlling the operation of such means to locate a mating line of the sections in predetermined position relative to such members when the means is rendered inactive.

50 20. In mechanisms for inclosing articles

in wrappers with twisted ends and operative with tissue wrapper inclosures for cigars, etc., means for supporting the wrapped article during end-twisting operations, said means including a sectional ring-like gear, a supporting member for each gear section, said members being pivotally connected to permit relative movements toward and from a section-mating position, intermittently-operative gear-rotating means, mechanism for controlling the operation of such means to locate a mating line of the sections in predetermined position relative to such members when the means is rendered inactive, and means for providing the member relative movement during inactivity of the gear rotating means.

21. In mechanisms for inclosing articles in wrappers with twisted ends and operative with tissue wrapper inclosures for cigars, etc., means for supporting the wrapped article during end-twisting operations, said means including a sectional ring-like gear, a supporting member for each gear section, gear-moving means, and means whereby said section movements are limited to rotation in complete ring formation.

22. In mechanisms for inclosing articles in wrappers with twisted ends and operative with tissue wrapper inclosures for cigars, etc., means for supporting the wrapped article during end-twisting operations, said means including a sectional ring-like gear, a supporting member for each gear section, and means for rotating the complete ring-formation relative to and in a predetermined path in said members.

23. In mechanisms for inclosing articles in wrappers with twisted ends and operative with tissue wrapper inclosures for cigars, etc., means for supporting the wrapped article during end-twisting operations, said means including a sectional ring-like gear, a supporting member for each gear section, said gear sections and members having complementary means for producing a predetermined rotative path of movement of the complete gear formation in said members, and means for rotating the gear in said path.

24. In mechanisms for inclosing articles in wrappers with twisted ends and operative with tissue wrapper inclosures for cigars, etc., means for supporting the wrapped article during end-twisting operations, said means including a sectional ring-like gear, a supporting member for each gear section, said gear sections and members having complementary means for producing a predetermined rotative path of movement of the complete gear formation in said members, means for rotating the gear in said path, and means whereby said sections will be held against rotation when said ring-formation is incomplete.

25. In mechanism of the character described, a rotatable support including a sectional ring-like gear, supporting members for the gear sections movable toward and from a section-mating position, means for rotating the complete gear, and means for retaining the sections against movement when said members are out of such position.

26. In mechanism of the character described, a sectional ring-like gear, a pair of members for supporting said sections, said members being movable toward and from a section-mating position, gear rotating means carried by one member, and means operative on the other member for preventing movement of its section when out of mating position.

27. In mechanism of the character described, a sectional ring-like gear, a support therefor including a pivoted member movable toward and from a section-mating position, and means carried by said member for engaging its gear section when the member is out of such position, the activity of said means being controlled by the member movements.

28. In mechanism of the character described, a sectional ring-like gear, a support therefor including a pivoted member movable toward and from a section-mating position, an element carried by the member movable toward and from a section-engaging position, and means in the path of travel of said element for controlling its movements.

29. In mechanism of the character described, a sectional ring-like gear, a support therefor including a pivoted member movable toward and from a section-mating position, a spring-actuated pivoted element carried by said member and movable into and out of section-engaging position, and a stop in the path of movement of the element for preventing such engagement when the sections are in mating position.

30. In mechanism for inclosing articles in wrappers with twisted ends and operative with tissue wrapper inclosures for cigars, etc., means for supporting the wrapped article during end-twisting operations, said means including gripping mechanism adapted to receive and grip the wrapped article, means for rotating said gripping mechanism, gripping mechanism positioned opposite the ends of the supporting means and operative on the wrapper ends, said end gripping mechanisms being movable toward and from gripping position, the gripping movements being in advance of the article rotation.

31. In mechanism for inclosing articles in wrappers with twisted ends and operative with tissue wrapper inclosures for cigars, etc., means for supporting the wrapped article during end-twisting operations, said

means including gripping mechanism adapted to receive and embrace the wrapped article, and means for rotating said mechanism intermittently, in combination with 5 wrapper-end gripping mechanisms opposite the ends of the supporting means and movable toward and from gripping position, and means for holding said end gripping mechanisms stationary during such rotating 10 movements.

32. In mechanism of the character described and in combination, a rotatable support for and adapted to embrace the wrapped article, gripping mechanisms opposite the support ends and movable toward and from wrapper-end gripping positions, a rotatable shaft, gear connections between the shaft and the support to rotate the latter and including means for locking the support 15 against rotation during a portion of the shaft rotation, and means operatively connecting the shaft and said gripping mechanisms for moving said mechanisms, said latter means locking said mechanisms against 20 movement during support rotation.

33. In mechanism of the character described and in combination, a rotatable support for and adapted to embrace the wrapped article, gripping mechanisms opposite the support ends and movable toward and from wrapper-end gripping positions, a rotatable shaft, gear connections between the shaft and the support to rotate the latter and including means for locking the 25 support against rotation during a portion of the shaft rotation, and means operatively connecting the shaft and said gripping mechanisms for moving said mechanisms, said latter means being operatively timed to 30 provide mechanism movements while the support is locked.

34. In mechanism of the character described and in combination, a rotatable support for and adapted to embrace the wrapped article, gripping mechanisms opposite the support end and movable toward and from wrapper-end gripping positions, a rotatable shaft, gear connections between the shaft and the support to rotate the latter and including means for locking the support against rotation during a portion of the shaft rotation, and means operatively connecting the shaft and said gripping mechanisms for moving said mechanisms, 45 said latter means being operatively timed to provide mechanism movements while the support is locked, said gear connections and gripping mechanism means being relatively timed to have non-concurrent activity during shaft rotation.

35. In mechanism of the character described and in combination, a rotatable sectional support for and adapted to embrace the wrapped article, the sections of the support being movable relatively to each other,

gripping mechanisms opposite the support ends and movable toward and from wrapper-end gripping position, a rotatable shaft, means operatively connecting the shaft and support to rotate the latter intermittently, 70 means operatively connected to the shaft for providing section movement intermittently, and means operatively connecting the shaft and gripping mechanisms for providing mechanism movements intermittently, said 75 several operating means being relatively timed to provide the following cycle of operations: open the sections to receive the wrapped article, close the sections, grip the wrapper ends, rotate the support, release the 80 grip, and open the sections to remove the completely wrapped article.

36. In mechanism of the character described and in combination, a rotatable sectional support for and adapted to embrace the wrapped article, the sections of the support being movable relatively to each other, gripping mechanisms opposite the support ends and movable toward and from wrapper-end gripping positions, a rotatable 90 shaft, means operatively connecting the shaft and support to rotate the latter intermittently, means operatively connected to the shaft for providing section movement intermittently, and means operatively connecting the shaft and gripping mechanisms for providing mechanism movements intermittently, said section moving means and the gripping mechanism means being rendered 95 active by shaft rotation during inactivity of the support-rotating means.

37. In mechanism of the character described and in combination, a rotatable sectional support for and adapted to embrace the wrapped article, the sections of the support being movable relatively to each other, gripping mechanisms opposite the support ends and movable toward and from wrapper-end gripping positions, a rotatable shaft, means operatively connecting the shaft and support to rotate the latter intermittently, means operatively connected to the shaft for providing section movement intermittently, and means operatively connecting the shaft and gripping mechanisms for providing 105 mechanism movements intermittently, said support rotating means being rendered active by shaft rotation during inactivity of the section-moving and gripping mechanism 110 means.

38. In mechanism of the character described and in combination, rotatable means for receiving and embracing a wrapped article, and mechanism for gripping a wrapper end during means rotation, said gripping 125 mechanism including a pair of fingers, an endwise movable support for the fingers, a stop in the advance path of movement of the support, cam means for closing the fingers, and means for moving the cam means axi- 130

ally a distance greater than the movement of the support; whereby the fingers will be advanced prior to being closed.

39. In mechanism of the character described and in combination, rotatable means for receiving and embracing a wrapped article, and mechanism for gripping a wrapper end during means rotation, said gripping mechanism including a pair of fingers, an 10 endwise movable support for the fingers, a stop in the advance path of movement of the support, cam means for closing the fingers, and means for moving the cam means axially a distance greater than the movement of 15 the support, whereby the fingers will be advanced prior to being closed, said stop preventing advance movement of the fingers while in gripping position.

40. In mechanism of the character described and in combination, rotatable means 20 for receiving and embracing a wrapped article, a table, a shaft below said table, a plate adjustable on said table toward and from said means, and wrapper-end gripping 25 mechanism carried by said plate, said mechanism including a pair of fingers movable toward and from gripping position, a cam on said shaft, and operative connections between the shaft and said fingers to successively advance and close them, said fingers 30

and operative connections being carried by and movable with the plate, and means carried by the plate for maintaining the position of the cam on the shaft, whereby the gripping mechanism, cam and plate are adjustable as a unitary structure. 35

41. In mechanism of the character described, means for gripping an untwisted end of a wrapped article, said means including a support, a pair of pivoted fingers on 40 said support, means for closing said fingers to gripping position, and adjustable means for positioning the fingers on their pivots and in the direction of pivotal movement whereby the gripping positions of the fingers 45 may be varied.

42. In mechanism of the character described, means for gripping an untwisted end of a wrapped article, said means including a support, a pair of elements pivoted to 50 the support, fingers movable with the elements, means for moving the elements to close the fingers to gripping position, and adjustable means for positioning each finger pivotally relative to its element to permit 55 variation in gripping positions of the fingers.

In testimony whereof I affix my signature.

GEORGE M. WILLIAMS.
